UNITED STATES PATENT OFFICE

2,474,848

TOOL FOR ASSEMBLING CARBINE BOLTS

Paul E. Kern, Lebanon, Pa.

Application July 18, 1946, Serial No. 684,440

1 Claim. (Cl. 29—268)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to tools, and more particularly to a type for facilitating the removable of the firing pin, the extractor and the ejector from the bolt of a carbine calibre .30 M1.

An object of the invention is to provide a device of this character, into which the bolt may be quickly and easily inserted and positively held during assembly or disassembly.

Another object of the invention is to provide a device, which while holding the bolt securely, will also depress the extractor and ejector plungers and hold them against escape from their sockets until it is desired to remove them.

A further object of the invention is to provide a device, which will be sturdy, inexpensive to manufacture and will be easily kept in working condition.

Other objects and advantages of the invention will be apparent during the course of the following description.

In the accompanying drawings, forming a part of this specification and in which like reference characters are employed to designate like parts throughout the same,

Figure 1 is a side elevational view of a tool embodying the present invention, showing a rifle bolt seated therein, in position to be disassembled,

Figure 2 is a vertical longitudinal section thereof, approximately on the line 2—2 of Figure 4,

Figure 3 is a vertical transverse section thereof, approximately on the line 3—3 of Figure 2,

Figure 4 is a horizontal transverse section thereof, taken through the pivoted joint and showing the bolt and one jaw in plan,

Figure 5 is a fragmentary view similar to Figure 4 showing the recesses for holding the bolt in the jaw, and

Figure 6 is a similar view taken on the line 6—6 of Figure 2.

A standard carbine .30 caliber bolt is shown to illustrate one use of the device, but it is to be understood that this bolt forms no part of the present invention.

In the drawing, wherein for the purpose of illustration is shown a preferred embodiment of my invention, the numeral 9 designates generally a carbine bolt. This bolt houses a firing pin 10 which has a tang 11 at one end and a restraining notch 12 near the other end. Also housed in the bolt 9 is a spring pressed ejector plunger 13, having a restraining notch 14.

2

The bolt 9 has a transverse bore 15 for receiving a pivot pin 16 which forms a part of an extractor 17. The pivot pin 16 engages in the notch 12 of the firing pin 10 and the notch 14 of the ejector 13. A spring pressed plunger 18 is also provided for the extractor 17. The plunger 18 has its longitudinal axis disposed at an angle to the longitudinal axis of the bolt.

Near its end adjacent the extractor 17, the bolt 9 is formed with a locking lug 20 and a cam lug 21.

All of the foregoing structure is old as has been stated.

Due to the smallness of the parts and to their location with respect to each other, it has been difficult, in the past to assemble these elements by hand without losing some to the spring pressed parts, or injuring the fingers of the assembler.

The present invention has been devised to overcome these difficulties and is herein disclosed as comprising two heads, movable toward and away from each other, each head being shaped to perform its function as will be shown.

A first jaw 22 is provided with a bore 23 forming a part of a seat for the reception of the bolt 9. At one side of the bore 23 and opening thereto is a slot or key-way 24, through which the firing pin tang 11 passes during insertion of the bolt 9 into the bore 23.

A shoulder 25 is formed in the jaw 22 to serve as a support for the locking lug 20 of the bolt 9.

Arising a suitable distance above the shoulder 25 at each side thereof are parallel walls or abutments 26 which serve to confine the lug 20 in a predetermined position.

A second shoulder 27 is formed in the jaw 22 to serve as a support for the cam lug 21. This shoulder 27 is located at the side of the bore 23 opposite to the seat 25.

At each side of this shoulder also are formed walls or abutments 28 snugly embracing the cam lug 21. The bore 23, the shoulders 25 and 27 together with the abutments all contribute in holding the bolt in a predetermined position, against rotation or longitudinal movement.

A second jaw 29 is provided, and is adapted to be moved toward and away from the first jaw 22 as will appear later.

When the bolt 9 is properly positioned in its seat in the first jaw, and the two jaws are moved toward each other, the ejector 13 comes into substantial axial alignment with an adjustable pressure finger 30 threadedly engaged in a bore in the second jaw 29. A locking nut 31 is threaded onto

the outer end of the presser finger 30 for maintaining a fixed adjustment thereof.

A recess 32 is formed in the jaw 29 to such a depth that a pawl 33 can be mounted therein in alignment with the spring pressed plunger 18 of the extractor 17. The pawl 33 is pivotally secured to the jaw 29 by a pivot element 34, and is yieldingly held against one wall of its recess by a spring 35. The inwardly extending end of the pawl is formed with a contact tooth 36 which will engage the extractor plunger 18. When the jaws 22 and 29 are moved toward each other the tooth 36 of the pawl 33 will first contact the inclined face of the extractor 17, and thereafter be cammed onto the plunger 18. A similar tooth 37 is formed on the outwardly extending end of the pawl 33. It will be apparent, upon examination of the drawing, that the pawl 33 is reversible so that either tooth 36 or 37 may be used in the event that one becomes broken or deformed.

The jaw 22 is provided with a handle 38 which is formed, at its junction with the jaw, with a pivot receiving lug 39. A handle 40, for the jaw 29, is likewise provided with a similar pivot receiving lug 41.

The portions 39 and 41 are formed with aligning bores to receive a pivot element 42. This connection is conventional and may be varied as the requirements of shop or field practice dictate.

The operation of the device is as follows:

It should be understood at this point that the firing pin, ejector and spring, extractor and spring pressed plunger, are all held in the bolt by one element, that element being the extractor pivot pin 16. Should this pivot pin be driven out, all of the above named parts would be propelled outwardly by their springs to some distance, and on occasions lost. The present invention has been devised to overcome these difficulties in assembly and disassembly.

The end of the bolt 9, remote from the lugs 20 and 21, is inserted into the bore 23 of the jaw 22 and rotated until the tang 11 of firing pin 10 comes into alignment with the slot 24. The bolt may then be fully inserted until the lugs 20 and 21 are at rest on their respective shoulders 25 and 27.

At this time the bolt and lugs are firmly held against rotation so that the elements to be removed or replaced cannot be moved out of the paths of the finger 30 and the pawl 33. The jaws are now moved toward each other by means of their handles.

The pivoted pawl 33 is so designed that its

tooth 36 comes into contact with the extractor plunger 18 near its outer end and retracts the said plunger when pressure is applied to the handles 38 and 40 to close the jaws. This action causes the pawl 33 to rock on its pivot 34 against the tension of its spring 35 and let its tooth 36 follow the line of motion of plunger 18.

Simultaneously with this operation the presser finger 30 is brought to bear on the ejector 13 and causes retraction thereof against its spring.

All spring pressed parts are then safely held and the ejector pivot pin 16 may be driven out or inserted into its bore 15, as desired.

It is to be understood that the form of the invention, herewith shown and described, is to be taken as a preferred example of the same, and that various changes in the shape, size and arrangement of parts may be resorted to, without departing from the spirit of the invention, or the scope of the subjoined claim.

Having thus described my invention, I claim:

An assembly device for firearm bolts comprising a pair of pivoted jaws, one of said jaws having a bore therethrough perpendicular to its inner surface and having formed on said inner surface two oppositely disposed recesses opening into said bore; the other of said jaws having a slot therethrough perpendicular to its inner surface to accommodate a spring biased pawl pivoted therein, said pawl having a forwardly directed tooth terminating intermediate the inner surfaces of said jaws, said other jaw also having a presser finger fixed therein perpendicular to its inner surface and positioned forwardly and laterally of said pawl, one end of said presser finger terminating in a section of reduced diameter intermediate said inner surfaces.
